UNITED STATES PATENT OFFICE.

JAMES L. LUND, OF NEW YORK, N. Y.

CLEANING-MACHINE.

1,273,077.

Specification of Letters Patent. Patented July 16, 1918.

Application filed February 28, 1916. Serial No. 80,828.

To all whom it may concern:

Be it known that I, JAMES L. LUND, a citizen of the United States, and a resident of New York, borough of Manhattan, county and State of New York, have invented certain new and useful Improvements in Cleaning-Machines, of which the following is a specification.

This invention relates to devices for cleansing pliable and more or less porous articles, such as garments and the material of which garments and articles of wearing apparel generally are or may be made, having more particularly in mind the removal of dust, dirt and other objectionable foreign matter, including loose hairs from fur, either in made-up form or in the piece. As a rule, furs are preferably cleansed by the ordinary beating process, the beater being manipulated by hand, or, as is often the case, by the employment of a device which includes a mechanically-actuated beater.

The most serious objection to the beating process, as employed heretofore, is the consequent throwing off into the atmosphere of the dust and loose hairs that are dislodged, which is obviously most unsanitary in that these minute particles of matter are taken into the lungs and nasal passageways of operatives and employees. While the underlying principle of the present invention is the provision, in connection with a suitable beating device, of means for creating and controlling air currents so directed as to collect the dislodged particles of solid or foreign matter and discharge the same into a suitable receptacle therefor, or into the atmosphere at a point where their dissipation will be unobjectionable, still the present invention more particularly contemplates such an arrangement of parts as to combine a maximum degree of cleansing efficiency with compactness and ease of manipulation. Furthermore, I have in mind the provision of a device having a wider range of usefulness than that possessed by prior devices of this character, as will appear from the following description.

My invention will be more readily understood by reference to the accompanying drawings, forming a part of this specification, in which—

Figure 1 is a side elevation of a complete device embodying my invention;

Fig. 2 is an enlarged end view thereof, partly in section taken substantially on the

line 2—2 of Fig. 3, the suspending means and the dust collector being broken away;

Fig. 3 is a central sectional elevation thereof, taken substantially on the line 60 3—3 of Fig. 2;

Fig. 4 is an enlarged central vertical section of the gears and gear mountings of the beater-actuating mechanism, showing the means for cutting out the beater when 65 desired, as hereinafter described, and

Fig. 5 is an enlarged sectional detail view taken substantially on the line 5—5 of Fig. 3.

Referring now to the drawings in detail, 70 numeral 7 refers to the casing of an electric motor, which, as it may be of any well-known and approved construction, and energized in the usual manner from any suitable source of electric energy, is not shown 75 in detail. This motor is provided with the usual motor shaft 8, which projects through the casing on both of the opposite sides thereof.

In view of the fact that the purpose of 80 the device is to dislodge and drive into the atmosphere small particles of solid matter, in addition to controlling the direction of movement of these particles for final discharge under conditions of harmlessness to 85 operatives and employees, it is manifestly most desirable, to protect the bearings and moving parts of the machine against the accumulation of dust and the like, and to this end, in providing a suitable casing to 90 95 so control the air currents as to retain these small particles of solid matter, I keep in view incasement of the bearings and machine parts. After many months of experiment, I have devised the casing shown in 95 the drawings, which includes, first, what may be termed a primary casing, this being the shell 9, within which the beater 38 oscillates and which may be said to be of downwardly-flaring or substantially dome-shaped configuration, the bottom thereof being open. This casing 9 is suitably secured to what I shall term the fan casing 10, the latter being of substantially cylindrical configuration, and being secured to the 100 flange or rim 11 of the motor casing 7 in such manner that the motor shaft 8 projects centrally thereinto. On this projecting end of the motor shaft 8, within the casing 10, is mounted the rotary fan 12, and the casing 10 is provided, on the side opposite the motor, with a central orifice which regis-

100

ters with an orifice in the upper portion of the casing 9 secured to and carried by said casing 10.

To the end of the casing 9, is secured what 5 may be termed a secondary casing 13, which incloses the beater-actuating mechanism, and the upper portion of which is secured to and supported by the motor casing 7. This 10 secondary casing includes plates 14 and 15, in which is journaled a shaft 16 carrying a gear 17 in mesh with a pinion 18 mounted on the end of the motor shaft 8 which projects into said casing. Mounted on the shaft 16, is the eccentric 19 carrying the eccentric 15 strap 20, the lower end of which is secured to the end of the beater-arm 21 preferably by means of a universal joint 22. This beater-arm 21 is pivotally mounted upon the shaft or rod 23 carried by the casing 13, 20 and preferably is of a configuration which provides a horizontal portion which curves downwardly and terminates in a seat or socket 24 for the beater-head, so as to properly position the latter for the beating operation. It will be apparent that upon rotation of the shaft 16, the eccentric 19 will cause oscillation of the beater arm 21 so as to vibrate or oscillate the beater 38 very rapidly between the positions indicated by 25 30 the solid and dotted lines in Fig. 3.

On the upper side of the fan casing 10, I provide a discharge conduit 25, and for the purpose of this description I have shown mounted on the end thereof a dust collector 35 26, which may be of any well-known construction, and which I prefer to employ in order to make the device more easily manipulated, for if this conduit were made to lead through any form of flexible tubing to 40 a point of discharge outside the room or chamber, for example, it is apparent that more difficulty would be experienced in moving the device from place to place and readjusting the same in different locations.

45 Cleansing operations such as those to which I have referred are generally performed upon a suitable work-stand or table, upon which the garment or other article to be cleansed is spread out, and, as it is necessary to move the device laterally over the 50 face of the garment while the beater is in operation, it is desirable that supporting means be provided for the device as a whole which will permit of such movement with 55 the least possible manual exertion. To this end, while it will be apparent that the device may be mounted for ready lateral movement over the work in many different ways, I prefer to suspend the same, and in the 60 drawings I have shown a bail 27, the ends of which are secured to opposite sides of the motor casing 7, this being substantially the plane, in the device as shown, in which the machine might be suspended most nearly in 65 balance. A suspending rod 28 has a hook 29

at the lower end thereof and in engagement with said bail, and this rod 28 is suspended preferably from a carriage 30, having grooved wheels 31 31 adapted to travel on a wire or track 32, whereby the device may be 70 readily moved back and forth. I have shown coil springs 33 33 interposed in the suspending means, whereby the vertical position of the device may be regulated, and I have also shown the rod 28 divided, the ends 75 thereof being connected by means of the block 34, whereby the suspending means may be lengthened or shortened to suit the requirements, finer adjustment being provided for by the manner of connecting the springs 80 33 to the carriage 30.

I have referred to the fact that it is sometimes desirable to utilize the suction created by a device of this character without operation of the beater. Thus, after one or 85 more cleansing operations have been performed, dust, dirt and hairs may be removed from the work-stand or table by continuing the operation of the fan, without, however, operating the beater, the device being moved 90 back and forth over the face of the stand or table in the same manner as when a garment or other article is being cleansed. In order to cut out the beater for this purpose, I mount the gear 17 loosely on the shaft 16, 95 and provide the former with a sleeve 35 (Fig. 4) projecting beyond the end of the shaft 16, whereby said gear and shaft may be locked together by means of a screw 36 threaded longitudinally into said shaft and 100 the head thereof frictionally engaging the end of said sleeve. Obviously, when this screw is loosened, the gear 17 will rotate loosely upon the shaft 16, and the beater will not operate, but when the screw is tightened 105 these parts will be firmly locked together and the eccentric will be rotated to operate the beater.

Furthermore, while there is a certain amount of inherent resiliency in the beater, 110 which is most often constructed of ratan, and in the beater mountings, this is not infrequently insufficient to reduce the rigidity thereof to a point which would prevent early destruction of the beater, due to the strains 115 of sudden and oft-repeated change of movements thereof and the forces of impact against the stand or table. Also, the blows of the beater should be cushioned to insure against ill effects to the article being 120 cleansed. Therefore, I prefer to divide the beater arm 21 into telescoping parts having limited lateral play, pivoted together at 37 (Figs. 3 and 5) and having a coil-spring 39 interposed to cushion the effect of 125 both the impelling forces of the actuating mechanism and the blows of the beater.

A pivotally-mounted door 40 affords provision for fine regulation of the amount of vacuum created within the casing 9 by the 130

operation of the fan 12, without depending upon changes in the speed of the motor 7.

Although it is manifest that a rheostat for controlling the speed of the motor 7 may 5 be located wherever it may be found most desirable, I have shown the rheostat 41 as being secured to the end wall of the casing 13 within said casing, and provided with the usual contacts 42 and control lever 43.

10 Various modifications of minor details of my improved vacuum beating machine will doubtless readily suggest themselves to those skilled in this art, and I therefore do not desire to limit my invention to the specific 15 construction shown and described herein.

I claim as new, and desire to secure by Letters Patent:

1. A device of the character described, comprising a casing having a relatively 20 large opening at the bottom thereof and a relatively small opening at the top thereof leading to a discharge conduit, a fan mounted at the smaller opening adapted to direct a current of air therethrough, a beater 25 mounted at the larger opening of said casing, independently incased actuating mechanism for said beater, and a motor interposed between said fan and said actuating mechanism and adapted to operate both thereof. 30 2. A device of the character described, comprising a casing having a relatively large opening at the bottom thereof and a relatively small opening at the top thereof

leading to a discharge conduit, a fan mounted at the smaller opening adapted to direct a current of air therethrough, a beater 35 mounted at the larger opening of said casing, independently incased actuating mechanism for said beater, a motor interposed between said fan and said actuating mechanism and adapted to operate both thereof, said beater having yielding connection with its actuating mechanism.

3. A device of the character described, comprising a casing having a relatively 40 large opening at the bottom thereof and a relatively small opening at the top thereof leading to a discharge conduit, a fan mounted at the smaller opening adapted to direct a current of air therethrough, a 45 beater mounted at the larger opening of said casing, independently incased actuating mechanism for said beater, a motor interposed between said fan and said actuating mechanism and adapted to operate both 50 thereof, and means for disconnecting said beater from its actuating mechanism whereby said fan may be operated independently.

In testimony of the foregoing, I have hereunto set my hand in the presence of two 55 witnesses.

JAMES L. LUND.
